ATTORNEY

UNITED STATES PATENT OFFICE.

WALTER M. STEVENSON, OF SEATTLE, WASHINGTON.

SAFETY RAZOR.

Application filed November 14, 1922. Serial No. 600,843.

To all whom it may concern:

Be it known that I, WALTER M. STEVENSON, a citizen of the United States, residing at Seattle, in the county of King and State of Washington, have invented a certain new and useful Improvement in Safety Razors, of which the following is a specification.

My invention relates to improvements in safety razors and the objects of my invention are: to provide a safety razor blade of triangular cross sectional shape whereby the cutting edge of such blade will be substantially nonflexible and will not bend or spring even when cutting the heaviest and toughest beards.

To provide a safety razor blade of triangular cross sectional shape having longitudinally extending grooves on opposite sides thereof wherein a holder may be caused to engage for the purpose of firmly and securely holding the blade so that it may be sharpened.

To provide a holder for a blade of this nature that will make it impossible to cut the face with the blade and that will further make it impossible to shave when the razor is tilted at any angle except the proper cutting angle.

To provide a blade holder of simple and efficient construction that may be quickly and easily manipulated to insert or remove a blade, that will not clog easily or become filled with lather and that is easily cleaned and dried after it has been used.

Other and more specific objects will be apparent from the following description taken in connection with the accompanying drawings, wherein—

Figure 1 is a view in perspective of a razor blade of triangular cross sectional shape constructed in accordance with my invention;

Fig. 2 is a view in side elevation of my safety razor showing the blade in an operative position in the holder;

Fig. 3 is an enlarged view in cross-section through the holder and blade;

Fig. 4 is a view in cross-section similar to Fig. 3, except that the blade and upper cap or plate are removed;

Fig. 5 is a view in cross-section substantially on broken line 5, 5 of Fig. 3;

Fig. 6 is a somewhat diagrammatic view in front elevation on broken line 6, 6 of Fig. 3, showing the relation between the outside guard members and the intermediate guard members; and

Fig. 7 is a view in perspective showing a form of holder that is used in sharpening the blade.

Referring to the drawings throughout which like reference numerals designate like parts, I have shown a safety razor embodying a blade 8 of triangular cross-sectional shape, commonly known as a wedge blade, that tapers on substantially straight lines 65 from a relatively wide rear edge 9 to a sharp cutting or shaving edge 10 at the front, the angle of divergence between the two sides being great enough so that the thinner portion of the blade adjacent the cutting edge 70 10 will be strong and rigid enough so that it will not spring and bend even when the blade is used for cutting the coarsest and toughest beards.

The blade holder embodies a base body plate 11 having a downwardly bent rear end portion 12 to which a handle 13 is arranged to be detachably secured as by a threaded stud 14 on the end of the handle that screws into the plate portion 12. The ends of the 80 plate 11 are bent upwardly at substantially right angles thereto and are shaped so as to form tapered grooves 15 having ledges 16 on which one side of the blade 8 may rest and overhanging portions 17 with which the 85 opposite side of the blade may engage, the grooves 15 at opposite ends of the body plate 11 being just far enough apart to receive the ends of a blade 8.

The body plate 11 terminates at its front 90 end in a plurality of guard members 18, and in two wider blade supporting members 19 disposed one at each side of the plate 11 and each provided with an upwardly protruding blade positioning lug 20 against which the 95 edge of the blade may rest when the same is inserted for use. The guard members 18 are slightly below the plane of the blade supporting end members 19, as shown in Fig. 6, and each of said guard members curves 100 downwardly below the cutting edge of the blade as shown at 21 in Figs. 3 and 4.

The blade 8 is held in position in the grooves 15 by a cover plate 22 having a downwardly curved forward edge 23 that 105 rests upon the blade, a downwardly projecting rear edge 24 that engages with and presses against the rear edge 9 of the blade and downwardly projecting end plates 25 that fit over the upturned ends of the base 110 plate 11. The outer walls of the grooves 15 are punched or stamped to form pro-

tuberances 26 and the ends 25 of the cover plate are provided with recesses 27 that fit over said protuberance and hold the cover plate in the proper position. The resilience 5 in the ends 25 of the cover plate allow the same to spring outwardly enough to snap over the protuberance 26. The outer surfaces of the ends 25 of the cover plate are preferably scored as shown in Fig. 2, to 10 facilitate handling the same.

The front edge 23 of the cover plate 22 rests on the blade 8 and extends upwardly far enough above such blade, as shown in Fig. 3, so that the razor is placed on the 15 face with the ends of the guard members 18 and the outer surface of the cover plate resting against the face the cutting edge 10 of the blade will be applied lightly to the face at exactly the correct angle to cut most 20 efficiently. If the razor is tilted too far forwardly the ends of the guard members resting on the face will lift the cutting edge of the blade off of the face and in a similar manner if the razor is tilted too far to the 25 rear the cover plate 22 resting on the face will cause the guard members and cutting edge of the blade to be lifted off of the face. From the preceding description it will be seen that the guard members 18 and cover plate 30 22 arranged as shown and described constitute means for determining the angle at which the blade must be held relative to the face in shaving and further make it practically impossible to shave with the 35 razor if the same is applied to the face at other than the correct angle.

The cover plate 22 may be applied to or removed from the razor very quickly and easily by grasping the ends 25 of such cover 40 plate between the thumb and forefinger.

Blades 8 are inserted from the rear into the tapered slots 15 and are withdrawn in the same manner, the cover plate 22 necessarily being removed before a blade can be 45 inserted or removed. The downwardly bent portion 12 of the base plate 11 affords enough room below the rear edge of the blade to enable a person to grasp the same with the finger when the blade is to be removed.

50 The blade is supported at the two ends by the grooves 15 but does not rest on the base plate 11.

The blade by reason of its triangular shape

is non-flexible and does not need to be firmly grasped and supported near the cutting edge. 55 This non-flexible feature is a very decided advantage in cutting heavy and tough beards as hereinbefore pointed out.

The blade 8 is provided on opposite sides with longitudinally extending slots 28 60 wherein the edges 29 of a holding device 30 may engage for the purpose of holding the blade for stropping or sharpening, the blade being arranged to be slipped into the holding device from one end. The holding 65 device 30 may terminate in a stud 31 that will fit snugly within the end of the hollow handle 13 so that such handle 13 may be removed from the razor and used as a handle for sharpening the blade. 70

The foregoing description together with the accompanying drawings clearly disclose what I now consider to be the preferred embodiment of my invention, but it will be understood that this disclosure is merely illustrative and that such changes in the form, dimensions and arrangement of the various parts of the device may be resorted to as are within the scope of the following 75 claim. 80

What I claim is:

A safety razor embodying a blade holder formed of a base plate, a handle on said base plate, a downwardly bent portion at the rear of said base plate, tooth-like guard members at the front of said base plate, upwardly projecting end members at the ends of said base plate, tapered channels formed in said upwardly projecting end members, a triangular blade arranged to be inserted within said tapered channels, a cover plate, a downwardly bent forward edge on said cover plate arranged to rest on said blade, a downwardly bent rear edge on said cover plate arranged to fit over the rear edge of said blade, downwardly bent ends on said cover plate arranged to fit over the upwardly projecting end members of said base plate, and snap means for releasably securing said cover plate to said base plate. 95 100

In witness whereof, I hereunto subscribe my name this 1st day of November, A. D. 1922.

WALTER M. STEVENSON.
